ber 21, 1944, Serial No. 564,453

7 Claims. (Cl. 88—24)

1

This invention relates to optical systems for the photographic recording of electrical impulses on a moving film such as are used in sound recording, picture transmission, and the like, and this application is a division of my application Serial No. 349,515, filed August 2, 1940, now abandoned, which is also assigned to J. A. Maurer, Inc.

More particularly, the invention relates to optical systems of the class referred to above wherein a small mirror vibrated by an oscillograph galvanometer, or a similar device for translating electrical impulses into mechanical vibrations, modulates a light beam in accordance with the electrical impulses to be recorded. The mirror oscillograph recording optical systems known heretofore, however, have the disadvantage that the light flux from the recording light source, such as the filament of an incandescent lamp, is not efficiently utilized therein. This unfavorable condition is due to the fact that the aperture of the oscillograph mirror is the limiting aperture in the two co-ordinate planes of the known optical systems, and that it cannot be enlarged beyond a certain degree since the physical size of the mirror must be comparatively small in order to avoid distortions due to its mass. For a given light source, therefore, the amount of light flux reaching the moving film is unduly limited in those optical systems, and this limitation makes itself particularly felt when filters are used at some position in the optical system, for example, for selecting light rays of a certain wave length, or for other purposes.

Another drawback of the known mirror oscillograph recording optical systems is that a portion of the light flux from the recording light source is not effectively prevented therein from falling on parts other than the oscillograph mirror, or on the structure housing the optical system. This portion of the light flux is to some extent reflected diffusely, thus forming stray light even though the surfaces on which it is incident may be black. Such stray light is objectionable because it may cause an additional exposure of the moving film, which should be exposed only to light flux modulated by the oscillograph mirror.

It is, therefore, the primary object of the present invention to provide a mirror oscillograph recording optical system which is highly efficient as regards the utilization of the light flux from the recording light source.

Another object of the invention is the provision of such an optical system whose limiting aperture can, in one of its co-ordinate planes, be

2

made much larger than the aperture of the oscillograph mirror.

Another object of the invention is the provision of such an optical system wherein the formation of stray light is reduced to a negligible amount.

Another object of the invention is the provision of such an optical system which is particularly satisfactory as regards ease of manufacture and convenience of adjustment.

Another object of the invention is the provision of such an optical system which may be built with small physical size and at comparatively little cost.

Still other objects of the invention include those which are hereinafter stated or apparent, or which are incidental to the invention.

In the optical system according to the invention, the oscillograph mirror is adapted to vibrate about a horizontal axis while the film moves past the recording point in a substantially vertical direction, the recording point being the point at which the optical axis of the system strikes the film. The optical system also has means for forming a light spot of vertically graded light flux.

Further means are provided in the optical system which effect an imagery of this light spot in such a manner that it is conjugate to the recording point in both the vertical and horizontal planes of the optical system. Otherwise, however, the imagery of the light spot is different in the two co-ordinate planes. In the vertical plane, the light spot is first imaged at a horizontal slit by imaging means acting in the vertical plane and then at the recording point by imaging means acting in only the vertical plane, the horizontal slit being placed between the oscillograph mirror and the recording point. In the horizontal plane, on the other hand, an intermediate image of the light spot is formed substantially on the mirror by first imaging means which act in only the horizontal plane. The intermediate image, in its turn, is imaged at a position beyond the recording point by second

imaging means which act in only the horizontal plane, and re-imaged at the recording point by third imaging means which act in the horizontal plane. By virtue of this arrangement, the mirror is substantially at a common focus of two imaging means which act in only the plane containing its axis of vibration, and the limiting aperture in the horizontal plane is the apparent aperture—as seen from the recording point—of the second imaging means. The apparent aperture of the second imaging means, however, can easily be

40 intermediate image of the light spot is formed substantially on the mirror by first imaging means which act in only the horizontal plane. The intermediate image, in its turn, is imaged at a position beyond the recording point by second

45 imaging means which act in only the horizontal plane, and re-imaged at the recording point by third imaging means which act in the horizontal plane. By virtue of this arrangement, the mirror is substantially at a common focus of two imaging means which act in only the plane containing its axis of vibration, and the limiting aperture in the horizontal plane is the apparent aperture—as seen from the recording point—of the second imaging means. The apparent aperture of the second imaging means, however, can easily be

50 intermediate image of the light spot is formed substantially on the mirror by first imaging means which act in only the horizontal plane. The intermediate image, in its turn, is imaged at a position beyond the recording point by second

made at least ten times as large as the aperture of the oscilloscope mirror.

The means for forming the light spot, finally, include a recording light source and a screen with an opening. The opening is illuminated by light flux from the light source, and its intermediate image is formed substantially on the oscilloscope mirror as has been explained hereinabove. At the same time, an image of the light source is formed substantially on the mirror by the action of a condenser lens in the vertical plane. In this manner, substantially all the light flux entering the optical system through the opening is controlled by the oscilloscope mirror whereby the formation of stray light is reduced to a negligible amount.

In the foregoing brief explanation of the state of the art and summary of the invention, and throughout the present specification, the term "co-ordinate planes" designates two planes at right angles to each other whose line of intersection is the optical axis of the system. The horizontal plane is the co-ordinate plane which contains the axis of the oscilloscope mirror and the slit, while the vertical plane is the co-ordinate plane at right angles to the horizontal plane. The plane of the slit, finally, is the plane which contains the slit, and is at right angles to both the vertical and horizontal planes.

In the present specification, the terms "vertical" and "horizontal" thus are not used in any absolute sense but merely in order to distinguish between two planes, or directions, at right angles to one another, and choice between those terms has been determined solely by convenience in description and illustration.

The invention will be better understood when the following description is considered with the accompanying drawings of certain presently preferred embodiments thereof, and its scope will be pointed out in the appended claims.

In the drawings:

Fig. 1 is a diagrammatic perspective view of an optical system embodying the invention.

Fig. 2 is a diagrammatic longitudinal section in the vertical plane of the optical system shown in Fig. 1, the optical axis being represented as a straight line and an oscilloscope mirror as an aperture.

Fig. 3 is a corresponding section in the horizontal plane.

Fig. 4 is an elevation of a part of the optical system of Figs. 1 to 3.

Figs. 5 to 10a show in elevation modifications of the part shown in Fig. 4.

Fig. 11 is a diagrammatic perspective view of a modification of the optical system shown in Figs. 1 to 3.

Fig. 12 is a perspective view of a modification of a part shown in Fig. 11.

Fig. 13 is a perspective view of a modification of another part of the optical system of Figs. 1 to 3.

Fig. 14 is a diagrammatic longitudinal section in the vertical plane of another modification of the optical system of Figs. 1 to 3, and

Figs. 15 and 16 are perspective views of modifications of two more parts of the optical system of Figs. 1 to 3.

Referring first to Figs. 1 to 3, these figures show, by way of example, a variable area recording optical system which embodies the invention. The optical system has a light source such as the filament 10 of an incandescent lamp 11. The light flux from lamp filament 10 uni-

formly illuminates a triangular opening 13 in a screen 14 so that a uniformly illuminated triangular light spot is formed at screen 14. The light beam defined by lamp filament 10 and opening 13 proceeds through the optical system and is deflected by the mirror 17 of an oscilloscope galvanometer (not shown) or similar device for translating electrical impulses into mechanical vibrations. It thus has a part which is incident from opening 13 upon mirror 17, and a part which is reflected from mirror 17 towards the recording point 27. Recording point 27 is the point at which the optical axis of the system strikes the film 23, and film 23 moves past recording point 27 in a substantially vertical direction as indicated by the arrow 28.

More particularly, opening 13 is an isosceles triangle whose base extends horizontally, and mirror 17 is adapted to vibrate about an axis 18-18 which likewise extends horizontally. Furthermore, a horizontal slit 21 is formed in a screen 22 which is placed between mirror 17 and recording point 27.

A spherical condenser lens 12 is placed between lamp 11 and screen 14, and a cylindrical lens 15 which has its cylinder axis vertical, is placed between screen 14 and mirror 17. In front of mirror 17 there is placed a second spherical lens 19 which acts on the reflected as well as the incident part of the light beam proceeding through the optical system. A second cylindrical lens 42 which also has its cylinder axis vertical, is placed between mirror 17 and screen 22, while between screen 22 and recording point 27 there is placed a third spherical lens 43. Between spherical lens 43 and recording point 27, finally, there is placed a third cylindrical lens 41 which has its cylinder axis horizontal.

These six imaging means have focal lengths relative to the other parts of the optical system as follows (see Figs. 2 and 3):

Spherical lens 12 has one of its conjugate foci at lamp filament 10, and the other substantially at mirror 17, that is, either on mirror 17 or at a position close thereto. Cylindrical lens 15 has one of its conjugate foci at opening 13, and the other substantially at mirror 17 so that an intermediate image of opening 13 is formed substantially on mirror 17. Spherical lens 19 has one of its conjugate foci at opening 13, and the other at slit 21. Cylindrical lens 42 has one of its conjugate foci at the intermediate image of opening 13, and the other at a position A beyond recording point 27. Spherical lens 43 has one of its conjugate foci at position A, and the other at recording point 27. Cylindrical lens 41, finally, has one of its conjugate foci at slit 21, and the other at recording point 27.

By virtue of the arrangement described hereinabove of its various parts, the following imagery is performed in the optical system of Figs. 1 to 3:

In the vertical plane (Fig. 2), spherical lens 19 forms an image of the uniformly illuminated opening 13 in the plane of the horizontal slit 21. This image of opening 13 moves vertically across slit 21 when mirror 17 vibrates about the horizontal axis 18-18. As much of slit 21 as is illuminated by the image of opening 13, is imaged at recording point 27 by cylindrical lens 41. There thus is formed at recording point 27 a horizontal line image of the illuminated portion of slit 21, and this line image has sharp and distinct horizontal boundaries. Likewise in the vertical plane, spherical lens 12 forms an image of lamp filament 10 substantially on mirror 17, thereby filling mir-

ror 17 with light and also aiding in the uniform illumination of opening 13 by lamp filament 10.

In the horizontal plane (Fig. 3), cylindrical lens 15 forms substantially on mirror 17 the intermediate image of opening 13, and an image of the intermediate image is formed by cylindrical lens 42 at position A. The image at position A, in its turn, is imaged at recording point 27 by spherical lens 43. By virtue of this successive imagery of opening 13 in the horizontal plane, the horizontal line image at recording point 27 has, in addition to its sharp and distinct horizontal boundaries, also sharply defined ends.

Lenses 12 and 19 are spherical and hence have power in the horizontal as well as in the vertical plane. But their actions in the horizontal plane can be disregarded for the following reasons:

On account of its position and relative focal length, spherical lens 12 tends to image lamp filament 10 substantially on mirror 17 also in the horizontal plane. The action, however, of cylindrical lens 15 interferes with this imagery to such an extent that it becomes immaterial for attaining the objects of the present invention. On the other hand, the power of spherical lens 19 in the horizontal plane has no effect upon the actions of cylindrical lenses 15 and 42 on account of the proximity of spherical lens 19 to mirror 17 which is, in the horizontal plane, substantially at a common focus of cylindrical lenses 15 and 42. No actions, therefore, of spherical lenses 12 and 19 have been indicated in Fig. 3.

Lens 43 is likewise spherical and hence has power in the vertical as well as in the horizontal plane. But its action in the vertical plane is immaterial because, in this plane, its power is small compared to the power of cylindrical lens 41. No action, therefore, of spherical lens 43 has been indicated in Fig. 2.

Cylindrical lenses 15 and 42, in their turn, do not interfere with the imagery in the vertical plane since they have their cylinder axes vertical, and hence act in only the horizontal plane. Correspondingly, cylindrical lens 41 does not interfere with the imagery in the horizontal plane since it has its cylinder axis horizontal, and hence acts in only the vertical plane.

The imagery performed in the vertical and horizontal planes of the optical system of Figs. 1 to 3 thus brings it about that recording point 27 is conjugate to opening 13 in both co-ordinate planes. In the vertical plane, horizontal slit 21 is, with respect to spherical lens 19, conjugate to a horizontal line through opening 13, for example, the broken line a—a shown in Fig. 4. Since, furthermore, recording point 27 is in the vertical plane conjugate to slit 21 with respect to cylindrical lens 41, it is also conjugate to line a—a. The line image at recording point 27 hence is an image of line a—a as far as its vertical extension, or width, is concerned, and it is, according to a well known property of conjugates, made up of the light flux emanating from line a—a. Moreover, this light flux is brought to a focus at recording point 27 also in the horizontal plane, namely—as has been explained hereinabove—by the successive actions of cylindrical lenses 15 and 42 and of spherical lens 43. The line image at recording point 27 hence is an image of line a—a also as far as its horizontal extension, or length, is concerned. When, therefore, the horizontal line through opening 13 is short—as is, for example, the broken line b—b in Fig. 4—the line image is also short, while it is long when that

horizontal line is long—as is, for example, the broken line c—c in Fig. 4.

The particular horizontal line through opening 13 to which recording point 27 is conjugate, is determined by the angle of inclination of mirror 17. Normally, mirror 17 is adjusted so that at its rest position, that is, when no electrical impulses are applied to the oscillograph galvanometer on which it is mounted, recording point 27 is conjugate to line a—a, which line passes through opening 13 halfway between its tip and its base. When then the electrical impulses to be recorded are applied in known manner to the oscillograph galvanometer, mirror 17 vibrates in accordance therewith about the horizontal axis 18—18 and in such a manner that, when the amplitude of its vibration is a maximum, recording point 27 is conjugate to line b—b at the one extreme of its motion and to the line c—c at the other extreme thereof. The length of the line image at recording point 27 hence varies in accordance with the vibration of mirror 17 and, therefore, the electrical impulses to be recorded. A variable area track 28 thus is produced on film 23 as it moves past recording point 27.

As has been explained hereinabove, recording point 27 is conjugate to opening 13 or, more exactly, to a horizontal line through opening 13, in the horizontal as well as the vertical plane of the optical system of Figs. 1 to 3. The imagery, however, which results in this condition, is different in the two co-ordinate planes. In the vertical plane, opening 13 is imaged at slit 21 by spherical lens 19 which acts in the vertical plane, and slit 21 is imaged at recording point 27 by cylindrical lens 41 which acts in only the vertical plane. Since spherical lens 19 is placed in front of mirror 17 and images opening 13 immediately at slit 21, the light flux from opening 13 is—in the vertical plane—diffused at mirror 17. This is necessary because the vertical plane is the plane through which the light beam is deflected when mirror 17 vibrates about the horizontal axis 18—18, thereby selecting, in co-operation with the horizontal slit 21, horizontal lines through opening 13 which become conjugate to recording point 27.

In the horizontal plane, on the other hand, an intermediate image of opening 13 is formed substantially on mirror 17 by cylindrical lens 15, and this intermediate image is imaged at position A by cylindrical lens 42 and re-imaged at recording point 27 by spherical lens 43 which acts in the horizontal plane. Since cylindrical lenses 15 and 42 act in only the horizontal plane, mirror 17 is substantially at a common focus of two imaging means which act in only the plane containing its axis of vibration 18—18. For any given angle of inclination of mirror 17, therefore, the amount of light flux from opening 13 which is acted upon by cylindrical lens 42, is limited by the aperture of this lens rather than the aperture of mirror 17. Moreover, since the light flux acted upon by cylindrical lens 42 is brought to a focus at position A and thence focussed at recording point 27 by the action of spherical lens 43, the limiting aperture in the horizontal plane is not the actual aperture of cylindrical lens 42, but its apparent aperture as seen from recording point 27. The apparent aperture of cylindrical lens 42, however, may—in view of the action of spherical lens 43—be made at least twice as large as its actual aperture which, in its turn, may be made as much as five times as large as the aperture which it is practical to give to mirror 17. The limiting aper-

ture in the horizontal plane of the optical system of Figs. 1 to 3 hence can easily be made at least ten times larger than the aperture of mirror 17.

The result thus obtained by means of the novel imagery embodied, by way of example, in the mirror oscilloscope recording optical system of Figs. 1 to 3 represents a marked advance over the prior art. In the known optical systems, the light flux from the entrance position corresponding to opening 13 is diffused at the oscilloscope mirror in the two co-ordinate planes so that the mirror aperture is the limiting aperture of the optical systems also in the co-ordinate plane which contains the mirror axis. Since the physical size of the oscilloscope mirror must be comparatively small in order to avoid distortions due to its mass, the above condition has been a serious obstacle to an efficient utilization of the light flux in the prior art optical systems. The advantage gained in this respect by the imagery according to the invention is considerable because, as is well known to those skilled in the art, the efficiency with which the light flux from a given light source is utilized in an optical system, is approximately proportional to the product of the limiting apertures in the two co-ordinate planes of the optical system.

Another advantage of having, in the optical system of Figs. 1 to 3, mirror 17 substantially at a common focus of two imaging means which act in only the horizontal plane, is that small deviations of mirror 17 about a vertical axis have a negligible effect on the imagery in the horizontal plane. Mirror 17 need therefore be accurately adjusted only about the horizontal axis 18-18. This greatly increases the ease of adjustment of the optical system, and is particularly important when it is necessary to replace the oscilloscope galvanometer on which mirror 17 is mounted.

A further advantage of the imagery performed in the optical system of Figs. 1 to 3 resides in the fact that there is formed substantially on mirror 17 an image of lamp filament 10 by the action of spherical lens 12 in the vertical plane, and simultaneously the intermediate image of opening 13 by the action of cylindrical lens 15 in the horizontal plane. It thus is possible so to control the light flux entering the optical system through opening 13 that it is all incident within the working aperture of mirror 17. This result is best obtained when the focal length of spherical lens 12 and the position of lamp 11 are chosen so that the image of lamp filament 10 has a vertical dimension no larger than that of mirror 17, and when the focal length of cylindrical lens 15 and the position of screen 14 are chosen so that the largest horizontal dimension of the intermediate image is no larger than the horizontal dimension of mirror 17. If these conditions are fulfilled, all the light flux passing through opening 13 is subject to control by mirror 17, whereby the formation of stray light in the optical system is reduced to a negligible amount.

The employment, finally, of cylindrical lens 41 in the portion of the optical system between screen 22 and recording point 27 has certain inherent advantages: Cylindrical lens 41 may have a short focal length so that the optical system may be built with small physical size. Moreover, a cylindrical lens of short focal length is less expensive than a spherical lens, or lens system, well enough corrected to form, over the same distance, an equally sharp line image. The optical system of Figs. 1 to 3 may hence be built with greater compactness and at less cost than the

mirror oscilloscope recording optical systems known heretofore.

The optical system shown in Figs. 1 to 3 as an embodiment of the imagery according to the invention may be modified, without affecting the basic principles of its operation, as follows:

(1) Opening 13 in screen 14 is shown in Figs. 1 and 4, and has been described hereinabove, as being an isosceles triangle whose base extends horizontally. However, any other opening whose horizontal extension varies in a vertical direction, may be substituted for opening 13 to produce a variable area track on film 23. For example, the opening in screen 14 may be a right-angled triangle with one of the sides adjacent to the right angle extending horizontally as is the opening 30 shown in Fig. 5, or there may one or more sawtooth projections extend into it as they do into openings 31 and 32 shown in Figs. 6 and 7, respectively.

However, in the case of opening 13 the line image at recording point 27 is a horizontal line of light whose length varies at both its ends so that the variable area track produced on film 23 is symmetrical as is the track 28 shown in Fig. 1. With opening 30, on the other hand, the line image is a horizontal line of light whose length varies at only one of its ends so that the variable area track produced on film 23 is of the unilateral type in this case. With opening 31, furthermore, two horizontal lines of light, each varying in length at only one of its ends, are formed at recording point 27 so that two unilateral variable area tracks are produced on film 23. With opening 32, finally, there are formed at recording point 27 three horizontal lines of light, each varying in length at both its ends, so that three symmetrical variable area tracks are simultaneously produced on film 23.

Tracks of the type known as "push-pull" may also be produced on film 23 by combining in screen 14 two openings of the kind described hereinabove. For example, the two openings may be two isosceles triangles 33a and 33b arranged as shown in Fig. 8, or two right-angled triangles 34a and 34b arranged as shown in Fig. 9. With openings 33a and 33b, a class B push-pull symmetrical variable area track is produced, and with openings 34a and 34b a class B push-pull unilateral variable area track. Class A push-pull variable area tracks may be produced, for example, by providing in screen 14 two right-angled triangles adjacent to each other along a common side d-d so that together they form a parallelogram 35, as shown in Fig. 10. In a preferred arrangement for the production of class A push-pull variable area tracks, however, a portion 14a of screen 14 separates the two right-angled triangles 35a and 35b, as shown in Fig. 10a.

As in Fig. 4, the broken line a-a indicates also in Figs. 5 to 10a the horizontal line through the opening, or openings, in screen 14 which is normally conjugate to recording point 27 when mirror 17 is at rest.

The openings of vertically varying horizontal extension shown in Figs. 4 to 10a, and described hereinabove, all are bounded by one or more straight edges which are inclined with respect to the horizontal plane of the optical system. Since, furthermore, the variation in length of the horizontal line, or lines, of light at recording point 27 is effected only by those inclined edges, the lower portion of screen 14 may be

omitted if desired, as indicated in Fig. 5 by the broken line $e-e$, for example.

When any of the openings, or pairs of openings, shown in Figs. 4 to 10a is in screen 14 and receives light flux from lamp filament 10 through spherical lens 12, there is formed at screen 14 a uniformly illuminated light spot whose horizontal extension varies in a vertical direction, or a pair of such light spots. The light flux emanating from this light spot, or light spots, hence is vertically graded.

Light spots of vertically graded light flux, however, may also have a uniform horizontal extension and a vertically varying illumination. Means for forming a light spot of this type are well known in the art. They may consist, for example, of the means disclosed by G. L. Dimmick in his U. S. specifications 2,095,317 and 2,095,318. These means include an opening 36 which is a rectangle with one of its sides extending vertically, and a penumbra stop 37, as shown in Fig. 11. But the illumination of rectangular opening 36 may also be varied vertically by associating with opening 36 a vertically graded light shading member 38 such as is disclosed, for example, in my U. S. specification 1,955,386 and shown in Fig. 12 of this specification.

When these or other suitable means for forming a light spot of uniform horizontal extension and vertically varying illumination are substituted for opening 13 in the optical system of Figs. 1 to 3—as shown by way of example in Fig. 11—the line image at recording point 27 is a horizontal line of light whose length is constant, but whose illumination varies in accordance with the vibration of mirror 17. Hence, a variable density track 39 is now produced on film 23 as it moves past recording point 27.

(2) It has been explained hereinabove that, while spherical lens 19 has power in both the vertical and horizontal planes, its action in the horizontal plane can be disregarded. Spherical lens 19 may therefore be replaced by a cylindrical lens 66 which has its cylinder axis horizontal and hence acts in only the vertical plane. Like spherical lens 19, cylindrical lens 66 has one of its conjugate foci at the opening in screen 14, and the other at slit 21. Cylindrical lens 66 may, furthermore, have the same position as spherical lens 19, in which position it is shown in Fig. 13. But since it acts in only the vertical plane, it may also have any other position between screens 14 and 22 which is consistent with its function to image the opening in screen 14 in the plane of slit 21. Spherical lens 19, on the other hand, should be placed close to mirror 17, as shown in Figs. 1 and 11, lest it interfere with the imagery in the horizontal plane.

(3) When the light beam defined by lamp filament 10 and the opening in screen 14 is incident upon mirror 17 at a sufficiently small angle, a single cylindrical lens 71 may be substituted for the two cylindrical lenses 15 and 42. Like cylindrical lenses 15 and 42, cylindrical lens 71 has its cylinder axis vertical, and it is placed so as to be traversed by the reflected as well as the incident part of the light beam proceeding through the optical system. The relative focal length of cylindrical lens 71 is so chosen that the opening in screen 14 and a position on, or close to, mirror 17 are conjugate with respect to cylindrical lens 71 on the incident part, and this position and position A are conjugate with respect to cylindrical lens 71 on the reflected part of the light beam. In this manner, cylindrical lens 71 forms the in-

termediate image of the opening in screen 14 substantially on mirror 17 and, simultaneously, images the intermediate image at position A.

The angle at which the light beam is incident upon mirror 17, may be made sufficiently small by considerably lengthening the optical system mechanically. However, this end may be accomplished in a more convenient way which, at the same time, provides for a very compact mechanical design of the optical system and which is shown, by way of example, in Fig. 14. It consists of placing a reflecting prism 70 between screen 14 and mirror 17 whereby the light beam is folded so that it is incident upon mirror 17 at a small angle, and cylindrical lens 71 is traversed by both the incident and reflected parts of the light beam. In place of prism 70 there may be employed other suitable beam folding means such as mirrors, or the like.

(4) Whenever it is desired to employ for the imagery in the horizontal plane of the optical system two lenses instead of the single cylindrical lens 71, cylindrical lens 42 may be replaced by a spherical lens 75 which, however, must be placed adjacent to screen 22 as shown in Fig. 15. When spherical lens 75 is so placed, its action in the vertical plane is barred by screen 22 so that it acts in only the horizontal plane. Spherical lens 75 may be placed on either side of screen 22, but must be close thereto in both cases lest it interfere with the imagery in the vertical plane.

Like cylindrical lens 42, spherical lens 75 has one of its conjugate foci at the intermediate image of the opening in screen 14, and the other at position A. The substitution of spherical lens 75 for cylindrical lens 42 has the advantage that a spherical lens at screen 22 is cheaper, and easier to adjust, than a cylindrical lens. The use of cylindrical lens 42, on the other hand, has the advantage that its position can be chosen independently of the position of screen 22, whereby the design of the optical system is facilitated.

(5) It has been pointed out hereinabove that, while spherical lens 43 has power in both the vertical and horizontal planes, its action in the vertical plane is immaterial. Spherical lens 43 may therefore be replaced by a cylindrical lens 44, shown in Fig. 16, which has its cylinder axis vertical and hence acts in only the horizontal plane. Like spherical lens 43, cylindrical lens 44 is placed between screen 22 and recording point 27 and has one of its conjugate foci at position A, and the other at recording point 27. The effect of cylindrical lens 44 upon the imagery in the horizontal plane thus is the same as that of spherical lens 43.

(6) Whenever the optical system of Figs. 1 to 3 is employed for producing a variable area track on film 23, it is desirable that the boundary, or boundaries, between the opaque and transparent portions of which this track consists, be sharp and well defined. The horizontal line, or lines, of light formed at recording point 27 must, therefore, be sharply defined at its, or their, ends. For that reason, cylindrical lenses 15 and 42, and spherical lens 43, should preferably be well corrected for spherical and chromatic aberration, and for coma. This applies also to their substitutes, namely, cylindrical lens 71, spherical lens 75, and cylindrical lens 44. However, if any or all of the above lenses are not so well corrected, the beneficial results accruing from their employment in accordance with the present invention may still be had, although to a lesser extent than if they are well corrected.

(7) If it is desired to employ the optical system of Figs. 1 to 3 for recording sound in accordance with the method generally known as "noiseless recording," the well known ground noise reduction systems may be used in conjunction therewith, as will easily be understood by those skilled in the art.

What is claimed is:

1. In an optical system, the combination of means for forming a light spot of vertically graded light flux; a mirror adapted to vibrate about a horizontal axis; means forming a horizontal slit; a recording point past which a film may move in a substantially vertical direction; first imaging means placed between said light spot and said mirror, and having first and second conjugate foci; second imaging means placed between said mirror and said slit forming means, and having third and fourth conjugate foci; third imaging means placed between said slit forming means and said recording point, and having fifth and sixth conjugate foci; fourth imaging means placed in front of said mirror, and having seventh and eighth conjugate foci; and fifth imaging means placed between said third imaging means and said recording point, and having ninth and tenth conjugate foci: said first imaging means acting in only the horizontal plane and having said first focus at said light spot, and said second focus substantially at said mirror so that an intermediate image of said light spot is formed substantially on said mirror; said second imaging means acting in only the horizontal plane and having said third focus at said intermediate image, and said fourth focus at a position beyond said recording point; said third imaging means acting in the horizontal plane and having said fifth focus at said position, and said sixth focus at said recording point; said fourth imaging means acting in the vertical plane and having said seventh focus at said light spot, and said eighth focus at said slit; and said fifth imaging means acting in only the vertical plane and having said ninth focus at said slit, and said tenth focus at said recording point.

2. The combination defined in claim 1 wherein said third imaging means is a spherical lens.

3. The combination defined in claim 1 wherein said second imaging means is a cylindrical lens having its cylinder axis vertical, and said third imaging means is a spherical lens.

4. The combination defined in claim 1 wherein said first and second imaging means are each a cylindrical lens having its cylinder axis vertical, and said third imaging means is a spherical lens.

5. The combination defined in claim 1 wherein said third imaging means is a cylindrical lens having its cylinder axis vertical.

6. The combination defined in claim 1 wherein said first and second imaging means are each a cylindrical lens having its cylinder axis vertical, said third and fourth imaging means are each a spherical lens, and said fifth imaging means is a

cylindrical lens having its cylinder axis horizontal.

7. In an optical system, the combination of a light source; a screen with an opening whose horizontal extension varies in a vertical direction, said opening being uniformly illuminated by said light source; a mirror adapted to vibrate about a horizontal axis; means forming a horizontal slit; a recording point past which a film may move in a substantially vertical direction; a first spherical lens placed between said light source and said screen, and having first and second conjugate foci; a first cylindrical lens placed between said screen and said mirror, and having third and fourth conjugate foci; a second cylindrical lens placed between said mirror and said slit forming means, and having fifth and sixth conjugate foci; a second spherical lens placed between said slit forming means and said recording point, and having seventh and eighth conjugate foci; a third spherical lens placed in front of said mirror, and having ninth and tenth conjugate foci; and a third cylindrical lens placed between said second spherical lens and said recording point, and having eleventh and twelfth conjugate foci: said first spherical lens having said first focus at said light source, and said second focus substantially at said mirror; said first cylindrical lens having its cylinder axis vertical and having said third focus at said opening, and said fourth focus substantially at said mirror so that an intermediate image of said opening is formed substantially on said mirror; said second cylindrical lens having its cylinder axis vertical and having said fifth focus at said intermediate image, and said sixth focus at a position beyond said recording point; said second spherical lens having said seventh focus at said position, and said eighth focus at said recording point; said third spherical lens having said ninth focus at said opening, and said tenth focus at said slit; and said third cylindrical lens having its cylinder axis horizontal and having said eleventh focus at said slit, and said twelfth focus at said recording point.

JOHN A. MAURER, JR.
